UNITED STATES PATENT OFFICE

FRANK J. KREMENTZ, OF NEWARK, NEW JERSEY, ASSIGNOR TO KREMENTZ & CO.,

CASE OR BOX.

No. 927,250.

Specification of Letters Patent.

Patented July 6, 1909.

Application filed July 2, 1908. Serial No. 441,684.

To all whom it may concern:

Be it known that I, **FRANK J. KREMENTZ**, citizen of the United States, residing at Newark, in the county of Essex and State of New Jersey, have invented certain new and useful Improvements in Cases or Boxes; and I do hereby declare the following to be a full, clear, and exact description of the invention, such as will enable others skilled in the art 10 to which it appertains to make and use the same, reference being had to the accompanying drawings, and to characters of reference marked thereon, which form a part of this specification.

15 The present invention has reference, generally, to improvements in that class of pocket-cases which are adapted for the purposes of carrying therein matches, cigarettes, and the like; and the invention relates, more 20 particularly, to a novel construction of pocket-case or box, having the marginal edges or portions of the hinged case-sections or members made with inwardly curling portions, said inwardly curling portions forming the sides and ends of the two case or box-members, so as to provide the proper depth 25 for the arrangement of cigarettes, and matches, usually the ordinary paper folders of safety matches, within the two hinged 30 sections of the pocket case or box.

This invention has for its principal object to provide a neat and simply constructed pocket-case or box of the general character stated; and, the invention has for its further 35 object to provide a pocket-case or box comprising a pair of hinged members which are made upon their marginal edges or upon portions thereof with the downwardly and inwardly curled portions to provide the sides 40 and ends of the case-members and to give the proper depth to the same, to provide great strength along the marginal edges of the hinged members or shells to prevent the buckling of the usually thin metal shells, 45 and to enhance the general appearance and beauty of a pocket-case or box of the general character hereinafter set forth.

Other objects of this invention, not at this time more particularly enumerated, will be 50 clearly understood from the following detailed description of the same.

With the various objects of my present invention in view, the same consists, primarily, in the novel pocket-case or box hereinafter 55 set forth; and the invention consists, further-

more, in the various novel arrangements and combinations of the several parts, and the details of the construction of the same, all of which will be hereinafter more fully described in the following specification, and then finally embodied in the clauses of the claim, which are appended to and which form an essential part of this specification.

The invention is clearly illustrated in the accompanying drawings, in which:—

Figure 1 is a face view of a pocket-case or box, embodying the principles of the present invention, the box being made for the purpose of storing matches, between its hinged members or shells; and Fig. 2 is a side view 70 of the box. Fig. 3 is a face view of the pocket-case or box with its hinged members or shells shown in their opened relation; and Fig. 4 is a transverse vertical section of the pocket-case or box with its two members or 75 shells closed down upon each other, and the said view being made upon an enlarged scale. Fig. 5 is an end view of a pocket-case or box made according to the principles of the present invention, and used for the 80 purpose of carrying cigarettes therein; and Fig. 6 is a plan view of the said pocket-case or box, showing the hinged members or shells in their opened relations. Fig. 7 is a detail transverse vertical section taken on 85 line 7—7 in Fig. 6; and Fig. 8 is a detail transverse section taken on line 8—8, also in said Fig. 6, and both of said views being made on an enlarged scale.

Similar characters of reference are employed in all of the above described views, to indicate corresponding parts.

Referring now to the several figures of the drawings, the reference-character 1 indicates a complete pocket-case or box which is 95 made according to and embodies the principles of my present invention, and the same comprises a pair of hinged members or shells, one of which I will hereinafter term the body or case-section 2, and the other I 100 will term the lid or cover-section 3. The said sections 2 and 3 which are made from suitable sheet metal have their main surfaces or body-portions curved outwardly, substantially as shown in the several figures of 105 the drawings, and the body-section 2 is made with the marginal edge-portions 4, curving in an upward direction, and then bent or formed into a marginal bead, 5, which terminates in a downwardly curved portion 6 and 110

an inwardly and upwardly curved portion 7, so as to provide the body-section 2 with a surrounding bead which is of a spirally formed or rolled-like cross-section, substantially as illustrated in Fig. 4 of the drawings. The upper case or cover-section 3 is made with the marginal edge-portions 8, curving in a downward direction, and then bent or formed into a marginal bead 9, which terminates in an upwardly curved portion 10 and inwardly and downwardly curved portion 11, so as to provide the cover-section 3 with a surrounding bead which is also of a spirally formed or rolled-like cross-section, as represented in said Fig. 4 of the drawings. It will thus be seen, that these spirally formed or rolled-like marginal beads constitute the sides and ends of the two sections 2 and 3, and thereby provide a pair of sections or shells of proper depths for retaining matches, cigarettes, and the like, within the two hinged sections when they are brought into their closed relations. The case-section 2 and the lid or cover-section 3 are respectively provided with suitably formed tubular members or ears 12 and 13, said tubular members 12 and 13 being adapted to dovetail together to form a hinged barrel, and being operatively and pivotally connected by means of a pintle 14, shown in end view in Fig. 2 of the drawings.

When the pocket-case or box is intended as a match box for the reception of the ordinary paper-folder of safety matches, the body or case-section 2 is provided with inwardly extending retaining or holding flanges 15 and 16, which are preferably flat, as shown in Fig. 3, and beneath which the paper-folder 17 containing the matches 18 and the scratching surface 19 can be slipped, and is removably held in its operative position within the depressed or chambered portion of the said body or case-section 2. The said flange 16 is usually provided with a suitably formed holding or locking post or stud 20 with which the inner surface of the marginal bead formed at one end of the lid or cover-section 3 can be brought in frictional engagement, so as to hold the two sections or shells 2 and 3 in their properly closed relation, as represented in Figs. 1, 2 and 4 of the drawings.

When the pocket-case or box is made for the purpose of carrying cigarettes, or for the purpose of carrying other articles of manufacture therein, such as loose matches, the spirally formed or rolled-like marginal bead of the main body or case-section 2 extends around the entire marginal surface of the said case-section, as illustrated in Fig. 6 of the drawings, the marginal bead being slotted or cutaway as at 21. Suitably secured to the inner surface-portion of the marginal bead, preferably by being soldered thereto, are a pair of retaining lugs or mem-

bers 22 behind which, and beneath the said bead, are suitably arranged and secured the respective end-portions of a spring-plate or bar 23. At its central portion, the said spring-bar or plate 23 is provided with an upwardly extending post-like member 24 which is formed at its free end with a catch-portion or nosing 25. A laterally extending finger or push-piece 26 is slidably arranged in the slotted portion 21 and is suitably connected with the said post-like member or element 24 by means of a screw 27, or other suitably formed fastening means. The marginal bead of the lid or cover-section 3 in this case is also cut away, as at 28, so as to form a retaining portion which is adapted to be snapped or sprung beneath the hooked-shaped end or nosing 25, in the manner indicated in Fig. 7 of the drawings, when the two sections or shells 2 and 3 are brought into their closed relation, as will be clearly evident. To separate the two sections or shells 2 and 3 all that is necessary is to press the fingerpiece 26 slightly in an inward direction whereby the hooked-shaped portion or nosing 25 will be moved away from its holding or retaining engagement with the slotted portion 28 in the marginal bead of the lid or cover-section 3, thus permitting the hinged sections or shells of the pocket-case or box to be brought into their separated or open relation.

It will be evident from the foregoing description and from an inspection of the several figures of the drawings, that the present invention provides a neat, convenient and simple, as well as a durable construction of pocket-case or box, the spirally formed or rolled-like marginal edge-beads producing great strength and enhancing the general appearance and beauty of the device, and at the same time providing the proper depth, for the purpose of carrying or storing matches or cigarettes, bou-bons, and other articles of manufacture within the case or box. At the same time, a neat pocket-case or box is provided in which there are no sharp edge either within or without the two sections or shells 2 and 3, so that the pocket-case can be safely carried in the pocket or shopping-bag without scratching or wearing the lining of the pocket or bag and without any danger of cutting the fingers while manipulating the device. It will be understood, that the said sections or shells 2 and 3 may be made of any metal or other suitable material, and may be made of any desired surface configuration or design.

I am aware that some changes may be made in the general arrangements and combinations of the various parts without departing from the scope of the present invention as defined in the claims which are appended to this specification. Hence I do not limit my invention to the exact arrangements

and combinations of the parts as described in the accompanying specification and as illustrated in the accompanying drawings.

I claim:

- 5 1. A pocket-case or box comprising a main body-section bounded by an upwardly curved portion, and a marginal bead connected with and extending partway around said curved portion, said bead terminating in a downwardly curved portion and an inwardly and upwardly curved portion, flat flanges extending from said first-mentioned upwardly curved portion, said flanges being adapted to receive a folder of matches, and a cover-section bounded by a downwardly curved portion and a marginal bead, said bead terminating in an upwardly curved portion and an inwardly and downwardly curved portion, substantially as and for the purposes set forth.
- 10 2. A pocket-case or box comprising a main body-section bounded by an upwardly curved portion, and a marginal bead con-

nected with and extending partway around said curved portion, said bead terminating in a downwardly curved portion and an inwardly and upwardly curved portion, flat flanges extending from said first-mentioned upwardly curved portion, said flanges being adapted to receive a folder of matches, and a cover-section bounded by a downwardly curved portion and a marginal bead, said bead terminating in an upwardly curved portion and an inwardly and downwardly curved portion, a hinge-connection between said sections, and a retaining catch on one of said flat flanges of the body-section, substantially as and for the purposes set forth.

In testimony that I claim the invention set forth above I have hereunto set my hand this 25th day of June, 1908.

FRANK J. KREMENTZ.
